UNITED STATES PATENT OFFICE.

WILLIAM A. LORENZ, OF HARTFORD, CONNECTICUT.

DESIGN FOR A CAN OR JAR.

SPECIFICATION forming part of Design No. 35,068, dated September 10, 1901.

Application filed August 12, 1901. Serial No. 71,844. Term of patent 14 years.

To all whom it may concern:

Be it known that I, WILLIAM A. LORENZ, a citizen of the United States, residing in Hartford, in the county of Hartford and State of Connecticut, have invented a new and original Design for Cans or Jars, of which the following is a specification.

My design relates to the external contour of cans, jars, and similar receptacles.

10 In the drawings, in which similar numerals designate corresponding parts, Figure 1 is a top view, and Fig. 2 a side view, of a can or jar embodying my design.

15 The substantially cylindrical body 10 of the jar is reduced at its upper end by a series of comparatively narrow annular steps 11, 12, and 13. Above the upper step 13 is the circumferential groove 14, which in turn is surrounded by the narrow and substantially cylindrical band or rib 15. The groove 14 is ap-

proximately semicircular in cross-sectional outline, its lower surface merging into the step 13 by means of a slightly-rounded corner 16. The rib 15 is smaller in diameter than the step 13, so that the series of steps 11, 12, 25 13, and 15 diminish in diameter toward the top of the jar.

Having described my invention, what I claim as new, and desire to secure by Letters Patent, is—

30 The design for a can or jar substantially as shown and described.

In testimony whereof I have signed my name to this specification in the presence of two subscribing witnesses.

WILLIAM A. LORENZ.
